UNITED STATES PATENT OFFICE.

WILLIAM J. H. STRONG, OF BELOIT, WISCONSIN.

DESIGN FOR A BASE OF A MOTOR-DRIVEN FAN.

48,204.

Specification for Design.

Patented Nov. 23, 1915.

Application filed August 7, 1915. Serial No. 44,328. Term of patent 14 years.

To all whom it may concern:

Be it known that I, WILLIAM J. H. STRONG, a citizen of the United States, residing at Beloit, in the county of Rock and State of Wisconsin, have invented a new, original, and ornamental Design for the Base of a Motor-Driven Fan, of which the following is a specification, reference being had to the accompanying drawing, forming a part thereof.

Figure 1 is a side elevation of the base of a motor-driven fan, showing my new design. Fig. 2 is a top plan view.

I claim:

The ornamental design for the base of a motor driven fan, as shown.

WILLIAM J. H. STRONG.
